UNITED STATES PATENT OFFICE.

ARTHUR MIDDLETON ROSE, OF YONKERS, ASSIGNOR TO W. & J. SLOANE,
OF NEW YORK, N. Y.

DESIGN FOR CARPET-BORDER.

SPECIFICATION forming part of Design No. 24,361, dated June 4, 1895.

Application filed May 6, 1895. Serial No. 548,344. Term of patent 3½ years.

To all whom it may concern:

Be it known that I, ARTHUR MIDDLETON ROSE, residing at Yonkers, county of Westchester, State of New York, have invented and produced a new and original Design for a Pattern to be Wrought in Wilton and Brussels Carpet Borders in such colors as may be desired, of which the following is a specification.

In the accompanying drawing, which forms a part of this specification, the elements of the design are shown without repetition.

The design consists of two principal figures which alternate.

The design is also indicated as wrought on a background, part of which is quite dark and extends from one edge to a little beyond the middle. This is represented by jet black in the drawing. The remainder of the back-

ground is of a lighter shade and is represented on the drawing by closely drawn vertical lines. Each of the two main ornaments lie partly over both parts of the background. Connecting the ornaments is a scrollwork which is on the dividing line between the two parts of the background.

What I claim, and desire to secure by Letters Patent, is—

The design for a carpet border, substantially as shown.

Signed by me, in New York city, this 4th day of May, 1895.

ARTHUR MIDDLETON ROSE.
